FLUID ACTUATED UNIT FOR CONVERTING RECIPROCATING MOVEMENT TO ROTARY MOVEMENT

Benjamin N. Ashton, Kingston, N.Y., assignor to Electrol Incorporated, Kingston, N.Y., a corporation of Delaware

Application August 21, 1957, Serial No. 47,466

Term of patent 14 years

(Cl. D55—1)

Fig. 1 is a top plan view of a fluid actuated unit for converting reciprocating movement to rotary movement showing my new design;

Fig. 2 is a side elevational view thereof;

Fig. 3 is an end elevational view thereof; and

Fig. 4 is an end elevational view thereof looking toward the opposite end thereof.

I claim:

The ornamental design for a fluid actuated unit for converting reciprocating movement to rotary movement, as shown.
